DESIGN FOR A LAMP

Frank M. Gaul, Decatur, Ill., assignor to Faries Manufacturing Company, Decatur, Ill., a corporation of Illinois

Application February 20, 1935, Serial No. 55,514

Term of patent 3½ years

To all whom it may concern:

Be it known that I, Frank M. Gaul, a citizen of the United States, residing at Decatur, in the county of Macon and State of Illinois, have invented a new, original, and ornamental Design for a Lamp, of which the following is a specification, reference being had to the accompanying drawing, forming part thereof, in which—

Fig. 1 is a side elevation of a lamp, showing my new design; and

Fig. 2 is a plan view of the base, the standard being in cross section.

I claim:

The ornamental design for a lamp as shown.

FRANK M. GAUL.
